DESIGN

No. 34,783.

Patented July 16, 1901.

J. SCHIES.
BOTTLE.

(Application filed June 12, 1901.)

UNITED STATES PATENT OFFICE.

JOHN SCHIES, OF ANDERSON, INDIANA.

DESIGN FOR A BOTTLE.

SPECIFICATION forming part of Design No. 34,783, dated July 16, 1901.

Application filed June 12, 1901. Serial No. 64,338. Term of patent 14 years.

To all whom it may concern:

Be it known that I, JOHN SCHIES, a citizen of the United States, residing at Anderson, in the county of Madison and State of Indiana, have invented and produced a new and original Design for Bottles, of which the following is a specification, reference being had to the accompanying drawings, forming part thereof, and in which—

10 Figure 1 is a side elevation of a bottle, showing my new design. Fig. 2 is a cross-sectional view on about line 2 2 of Fig. 1 on a slightly-enlarged scale. Fig. 3 is a cross-sectional view on about line 3 3 of Fig. 1, and Fig. 4 is a bottom end view of the bottle.

15 The leading or material feature of my design consists in the design of the body of the bottle forming the subject-matter of the accompanying illustration. This body is formed with the main portion A in the form of a cylinder, whose upper end at A' is continuous or unbroken, as best shown at Fig. 3, and upon the body A are formed below the continuous unbroken upper portion or head A' 20 the plurality of outwardly-bulged chambers or protuberances B, which extend longitudinally in the direction of length of the bottle, are curved transversely from side to side, as

shown in Figs. 2, 3, and 4, have their bottoms flat, as shown at B' in Figs. 1 and 4, and have 30 their upper ends curved longitudinally, as shown at B², leading into the body A of the bottle, and also curved from side to side, as shown at B³ in Fig. 1, producing the appearance represented in Fig. 1 of the drawings. 35 The upper end of the body A is represented as curving inwardly at a to its juncture with the neck C of the bottle.

It will be noticed from Figs. 1 and 2 that the portions A² of the body of the bottle which 40 lie between the protuberances B connect such protuberances, and the bottle presents in cross-section an appearance simulating that of the shamrock.

Having described my invention, what I 45 claim as new, and desire to secure by Letters Patent, is—

The design for a bottle as herein shown and described.

In testimony whereof I have signed my 50 name to this specification in the presence of two subscribing witnesses.

JOHN SCHIES.

Witnesses:

MARY SCHIES,

LEANDER K. ROYER.
